The ornamental design for a blank for packaging carton, as shown and described.

DESCRIPTION

FIG. 1 is a front view of a blank for packaging carton, according to our new design, in which the blank for packaging carton is shown in an unfolded configuration; FIG. 2 is a front view of the blank for packaging carton of FIG. 1 shown in a folded configuration; and, FIG. 3 is a rear view of FIG. 2.

The outermost solid lines in the views show the outer perimeter of the blank for packaging carton. The other solid lines in the figures indicate fold lines. The broken line in the figures depicts a line of perforation and does not form a part of the claimed subject matter.
